UNITED STATES PATENT OFFICE.

WILLIAM L. SAUNDERS, OF NEW YORK, N. Y.

METHOD OF DRIVING TUNNELS.

SPECIFICATION forming part of Letters Patent No. 413,869, dated October 29, 1889.

Application filed May 10, 1888. Serial No. 273,392. (No model.)

To all whom it may concern:

Be it known that I, WILLIAM L. SAUNDERS, a citizen of the United States, residing at New York, in the county of New York, State 5 of New York, have invented certain new and useful Improvements in Methods of Driving Tunnels, of which the following is a description.

My invention relates to improvements in 10 the art of tunneling in rock.

The enlargement of a tunnel or bore being a matter of detail and easily effected, the description of my improved method will be restricted to the formation of the pilot or heading, which offers the principal difficulties in forcing a passage through solid rock. In using the term "hard or solid rock" it is my intention to distinguish between soft or bituminous coal and all other material capable 20 of being undercut or channeled by hand-tools.

The method at present in use for driving headings through solid hard rock—such, for example, as granite—comprises the drilling of converging holes about the center line of 25 the heading and of a number of other holes at suitable distances therefrom. The converging holes are first fired, throwing out a chip or wedge-shaped mass between them, and thus forming a release or line of least resistance for the action of the explosive in the side holes. The side holes are then fired, 30 breaking out the intervening rock in the heading to the depth or extent of the cut produced by the blast of the converging holes.

It will be noted that in order to furnish a line 35 of less resistance upon which the explosives can act the center holes must converge to a point of coincidence at the bottom in order to break out the central portion forward and afford a lateral release for the explosives in 40 the side holes. It follows, then, that the angle of the central holes and the consequent progress of each cut or round will be limited by the width of the heading, since the said holes

45 cannot be put in at a greater angle than the converging sides of a triangle of which the width or height of the heading would form the base. In small headings the central holes are therefore necessarily shallow and the progress 50 but a few feet, sometimes not more than two or three at each round.

I am aware that soft coal has for years been

mined by the formation, whether by hand or machine, of a trench or cut along the lower line of the vein, this being accomplished 55 within a large chamber. After a body of coal has been undercut it sometimes falls of its own weight; but the usual practice is to apply wedges or gunpowder along the upper margin of the vein, thereby breaking down 60 the intervening mass, care being taken to reduce it as little as possible in order to keep it in marketable shape in lumps, not dust, and to economize the breakage during transportation. This method can have no bearing 65 upon my invention, for the reason that it deals only with comparatively soft substances capable of being undercut with an ordinary pick and the mass broken down by wedges and a hammer. Furthermore, it is carried on 70 in large chambers, where it is possible to use tools and to apply them in a manner wholly impracticable in a heading or shaft.

By my improved method the converging central holes are dispensed with, and it is 75 practicable to continue the drilling in the smallest heading until the advance cut and also the side holes have been made, say, from six to eight feet in depth, which is accomplished by substituting an artificial channel 80 or seam for the diagonal holes and the prismatic opening produced by blasting out the portion between them. The channel would ordinarily be formed in the ordinary central line of the heading, the drill-holes for the 85 explosives being properly located with reference thereto, so that when fired the rock between the said side holes and the central channel would be broken out, the channel affording a release or line of least resistance 90 therefor. By the use of a suitable channeling-engine mounted upon a column the cutting of the channel and the drilling of the side holes can be carried on simultaneously, so that at the end of each working shift the 95 desired working depth can be reached.

In sinking shafts the method of procedure is similar to that just described, the drilling and cutting being in vertical instead of in horizontal planes. In very small headings, 100 where there would not be room on each side of the channeling-machine to work the drills putting in the side holes, it is desired to place the channeling-machine as near to

one side as practicable, cutting the channel close to one side of the shaft or heading. The drills can then be simultaneously operated to put in two or more rows of holes between the 5 channel and the opposite side. In this instance it will be found desirable to first fire the row of holes adjacent to the channel, they having a free release thereinto, after which the remaining holes can be fired with the certainty 10 that they will produce maximum results on account of the release produced by the first line of holes toward the artificial seam or channel. By providing an effective release-line for the explosives in the blast-holes between the channel and the side or 15 sides of the heading, the rock will be much more effectively broken by the firing of said charges, and it is practicable to drill fewer and deeper holes and to use larger charges. Reducing the number of holes to be drilled 20 in connection with the artificial seam or channel enables the force which is available to sink them to a greater depth during each working-day, and therefore to penetrate farther in a given time with the limited force of 25 men and machinery capable of being accommodated in a heading.

Another advantage incident to my improved method results from the reduced 30 amount of explosives required. A suitable and efficient line of release being provided, the force of the explosives will take effect mostly in the desired direction, there will be less jar and shock, and the walls of the 35 tunnel will be much less shattered and broken than with the all-blasting method, thus diminishing the danger from falling rock. There will also be much less noxious gas generated by the blast, so that work may be begun earlier 40 after each round has been fired.

The machine with which the channel or artificial seam is cut is a form of combined channeling and gadding machine resembling that shown, described, and claimed in an application for Letters Patent filed by me June 45 17, 1887, Serial No. 240,816, but which is not, however, herein specifically claimed. The machine referred to is capable of radial or vertical movement upon a supporting-column, 50 and whether movable vertically or radially is employed, first, to drill holes of the desired depth at the extremities of the proposed channel. After the end holes have been drilled the drill-chuck is removed and a cross-head 55 and gang of chisels attached to the piston-rod and operated in the manner common to channeling-machines—that is, is caused to travel back and forth between the end holes, thereby cutting out the intervening material 60 and producing a channel of, say, one inch and a half in width, six feet in depth, and of a rectangular or triangular form, according to the manner of operating the channeling-machine. The channel, however, extends substantially 65 from the top to the bottom, or from side to side of the heading, so that in the case of a very small heading the blast-holes surrounding the

channel may be simultaneously fired and all have a sufficient release or line of least resistance in the direction of the channel, and so produce their maximum effect by breaking out the intervening rock with the least number of holes and the smallest quantity of powder. In the case of a very small heading, however, it may be found desirable to locate 70 the channel at one side, placing at least two rows of holes between the channel and the opposite side of the heading, whether the same be the roof or one side thereof. In this instance it will be found necessary to first fire the holes immediately adjacent to the channel, after which the remaining ones can be fired with the certainty that they will produce maximum results on account of the release produced by the explosions of the first 75 80 85 line of holes toward the artificial seam or channel.

My improved method can be applied and embodied in many different forms of apparatus, and, in fact, any mechanisms capable of 90 performing the work necessary to be accomplished and of being operated simultaneously in the restricted space of a heading will answer in the carrying out thereof. Some forms of such apparatus have been shown in the accompanying drawings, more, however, as a means of illustrating the method than for the purpose of limiting the invention to the use 95 thereof.

Figure 1 is a longitudinal elevation, partly 100 in section, showing a heading with a radially-mounted drill putting in the marginal holes of the channel or seam. Fig. 2 is an elevation, and Fig. 3 is an end view, showing the first stage of the forward progress in a heading. Fig. 4 is a view similar to Fig. 1, except that the drilling-engine has been relieved of its 105 rotative movement and provided with a set of chisels, and is adapted to operate as a radial channeler for the purpose of cutting out 110 the material between the end holes seen in Fig. 1. Fig. 5 is an elevation. Fig. 6 is an end view showing the final stage of the preparation of a heading for the blast. Fig. 7 is an elevation similar to Fig. 4, except that it 115 shows the channel being cut by a vertically-moving channeling-machine instead of the radially-mounted engine seen in Fig. 4. Fig. 8 is a view similar to Fig. 4, except that the work is progressing vertically downward 120 instead of horizontally. Fig. 9 is an end view of a small heading, showing the channel at one side. Fig. 10 is a view similar to Fig. 9 with the channel on the opposite side. Fig. 11 is a plan view showing the position of the 125 channel. Fig. 12 is a plan view of a portion of the heading driven with channels on alternate sides.

Similar letters denote like parts throughout.

As indicated in the drawings, A indicates 130 the shaft or heading, transversely of which is shown in Figs. 1, 4, 7, and 8 a drill-supporting column B. The column B is provided with foot-screws b, by which it is jammed be-

tween the roof and floor or between the side walls and firmly secured in the desired position. Upon the column B is fitted an adjusting-clamp C, which is provided with set-screws 5 C', by which it is securely fixed at any desired point between the ends of the column. The clamp C is provided with an opening or bearing D, constructed to constitute a clamp, a portion d of the walls of said opening being 10 hinged and provided with an adjusting-screw d', by which the size of said opening can be regulated as desired.

F represents the drilling-engine, of which f is the feed-screw and G the shell, the said 15 shell being formed with a continuation g at its lower end to support guides for the cross-head carrying the chisels when said drilling-engine is operating as a channeling-machine, as shown, described, and claimed in a pending 20 application, No. 240,816, filed by me June 7, 1887. The trunnion E fits into and is supported within the opening D in the clamp-block C, and by adjustment of the said screw d' the shell and drilling-engine can be rigidly 25 held in any desired position or be capable of radial movement upon the trunnion or pivot E. The margin of the clamp-block C opposite to the opening D is cut to form a segmental work-rack II, a worm - pinion h, mounted 30 upon the shell G and provided with suitable hand-lever h', being engaged therewith. By operating the hand-lever h' it will be understood that the drilling-engine as a whole is turned about its pivot, together with the drill 35 or chisels, as the case may be.

As indicated in Fig. 1, the drilling-engine F is employed in putting in a hole I, which said hole is at about that angle from the central line of the tunnel upon which, when driven 40 to the desired depth, the said hole will terminate upon the floor-line of the tunnel. The hole is in this instance assumed to be six feet in depth. A hole J is indicated as being completed, the said hole J being directed upward 45 at an angle similar but opposite to that of the hole I.

In Fig. 2 the completed holes are indicated, it being understood, however, that where drills longer than seven feet can be operated 50 with economy such drills will be used and the angles of the first two holes I J be such that the said drills will reach the limit of their depth and the roof and floor or side lines of the heading coincidently. While the holes 55 I J are being drilled side holes i i j j are also being put in, the positions of said holes being approximately indicated in Fig. 3, a very important feature of my improved method consisting in the feasibility of carrying on 60 both parts of the operation and simultaneously operating the different mechanisms required at the same time.

As explained in my said prior pending application, when the end holes I J have been 65 put in, the chuck f', carrying the drill F', will be replaced by a cross-head K, carrying a set of channeling cutters or chisels k, the cross-

head being suitably guided in the extended portion g of the shell G of the drilling-engine.

As indicated in Fig. 4, the drill has been 70 replaced by the chisels k and the operation of forming a channel between the marginal holes I J has made some progress. In removing this material a channel is formed by the chisels k, the operation of the machine being 75 directed and controlled by the hand-lever h' and worm - pinion h, by means whereof the drilling-engine is moved radially as desired and caused to operate as a channeling-machine. When the chisels have completed a 80 cut from the hole I to the hole J, or vice-versa, the chisels are fed downward by the feed-screw f the distance of the depth of the succeeding cut, when the radial movement is again imparted by means of the hand-lever h' and the 85 chisels k gradually moved in their radial path until the other drill-hole is reached. These operations are reversed until all the material between the drill-holes I J is removed, 90 leaving a triangular channel, as shown in Fig. 5, and as seen also in Fig. 6.

When a radially-mounted channeling-machine is employed, there will remain at top and bottom of the channel L a projection or offset L'. For the purpose of removing the 95 offset L' additional short holes l may be put in and fixed with the side holes.

As indicated in Fig. 7, the channeling-machine is arranged to be moved bodily up and down upon its supporting-column and always 100 in the same plane, the effect of such movement being to cut a rectangular channel M in place of a channel of triangular form, as shown at L. Instead of being provided with a pivot-bearing D and a segmental worm-rack II, the clamp-block C is in this instance secured positively to the shell G and provided with a screw-threaded opening parallel with the column B, through which passes a feed-screw B', which is pivotally mounted at its ends in a position parallel 105 with the said supporting-column B, whether the same be arranged vertically or horizontally. The travel of the channeling-machine is effected by a hand-lever N, which is provided with a collar n, fitting over the lower 110 portion of the feed-screw B', and said hand-lever N is provided with a pawl engaging a ratchet O, attached to the said feed-screw. The pawl N is of the well-known reversible character, so that by adjustment of said pawl 115 the lever N may be used to impart motion to the feed-screw in the desired direction, whether for raising or lowering the channeling-machine.

In small headings or other restricted spaces 120 where it is desirable to cut the channel L at one side of the heading, as indicated in Fig. 9, in order to afford space for the operations of channeling and drilling to be carried on at the same time, two or more rows of holes p q 125 are put in substantially parallel with said channel, and the said rows of holes are exploded successively, in order that the channel shall afford the release for the first row, and

the openings produced by the firing of the first row of holes afford the release for the next succeeding row. As seen in said Fig. 9, the first row only of said holes has been fired.

5 In headings necessitating the cutting of the channel at one side it will be found desirable to place the machine as near as possible to the side wall, inclining the cut outward, as indicated in Fig. 11. Frequent repetitions of 10 the inclined cuts shown in said figure would destroy the alignment of the tunnel. This difficulty is, however, obviated by placing the channel on alternate sides of the heading, as indicated in Fig. 12. The offsets L' left after 15 each round are subsequently removed.

In Fig. 10 the channel is indicated as upon the opposite side from the position shown in Fig. 9, and for the sake of illustration the effect of the firing of both rows of holes is 20 shown.

Having described my invention, what I claim, and desire to secure by Letters Patent, is—

1. The herein-described method of driving 25 tunnels of small sectional area in hard rock, which consists in making a first cut in the form of a narrow open channel driven into and across the face of the rock or heading and without the use of explosives, then placing 30 surrounding or adjacent drill-holes and blasting out the material between the channel and the wall or walls of the tunnel after the channel has been completed, substantially as described.

35 2. The herein-described improvement in the art of driving shafts or headings of small

sectional area in hard rock, which consists in making a first cut in the shape of a narrow open channel driven into and across the face of the rock or heading to the depth of the cut 40 and without the use of explosives, then placing surrounding or adjacent drill-holes and blasting out the material between the channel and the walls of the shaft or heading after the channel has been completed, substantially as described. 45

3. The herein-described method of driving tunnels of small sectional area in hard rock, which consists in making a first cut in the form of a narrow open channel extending 50 across the face of the rock or heading and of the depth of the proposed cut, said channel dividing or separating the material to be removed, and placing surrounding or adjacent drill-holes and blasting out the material between 55 the channel and the wall or walls of the tunnel, substantially as described.

4. The herein-described improvement in the method of boring or tunneling hard rock, which consists in cutting an open groove or 60 channel into and across the face of the heading and simultaneously drilling holes for the reception of explosives in the material between the channel and the wall or walls of the bore, substantially as described. 65

In testimony whereof I hereto affix my signature in presence of two witnesses.

WILLIAM L. SAUNDERS.
